(57) **CLAIM**

I claim the ornamental design for a castable umbrella rig with interchangeable wire harness, as shown and described.

DESCRIPTION

FIG. 1 is a perspective view of a castable umbrella rig with interchangeable wire harness of the design described herein.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

Portions of the lure are shown broken away to indicate indeterminate length.
